UNITED STATES PATENT OFFICE.

JAMES H. RAND, OF NORTH TONAWANDA, NEW YORK.

INDEX.

1,340,251.

Specification of Letters Patent.

Patented May 18, 1920.

Application filed August 20, 1918. Serial No. 250,727.

To all whom it may concern:

Be it known that I, JAMES H. RAND, a citizen of the United States of America, and resident of North Tonawanda, in the county 5 of Niagara and State of New York, have invented new and useful Improvements in Indexes, of which the following is a specification.

This invention relates to an overlapping 10 card, visible index, and consists in the novel and improved means for holding the cards or similar index elements in overlapped spaced relation, and in the other novel features, all as hereinafter described and particularly pointed out in the claims.

In the accompanying drawings which illustrate certain embodiments of the invention,—

Figure 1 is a front view of a group of 20 standing cards or index elements embodying the invention;

Fig. 2 is a face view of the blank from which one of said index elements is formed;

Fig. 3 is a rear view of one of said 25 elements;

Fig. 4 is a side or edge view of the group of cards assembled as shown in Fig. 1;

Fig. 5 is a front view of a group of depending cards or index elements embodying 30 the invention;

Fig. 6 is a face view of the blank from which one of said depending index elements is formed;

Fig. 7 is a rear view of one of said 35 depending elements; and

Fig. 8 is a side or edge view of the group shown in Fig. 5.

Referring first to the form of the invention shown in Figs. 1 to 4: Each card or 40 similar index element is made of cardboard, paper or other suitable sheet material, and comprises a body 1, having one margin folded over on itself, as on the line or fold 2, said folded margin being fastened to the body 1 part way from the fold by any suitable means. The preferred fastening means as herein shown consists of a row of metallic 45 fasteners or staples 3, arranged on a line parallel to the fold 2 and spaced inwardly 50 therefrom; but other fastening means, such as paste or glue, or stitching, are within the contemplation of the invention.

The end of the folded margin 5, beyond the fastening means, is left free, and is preferably creased on a line 4 adjacent to the part fastened to the card body, and bent

slightly away from the card body on said creased line to form an open spacing pocket, which engages the edge of the next adjacent card or element in the series, thus supporting the cards in upstanding, overlapped, nested and spaced relation, as shown, with their free margins exposed to display index characters.

Each card has a pair of integrally formed 65 projections 6, extending laterally from, and adjacent to, the folded edge of the card, to engage the usual channels of an index frame. The frame is indicated in dotted lines at F, the flanges which form the channels being 70 indicated at f f. Said projections 6 are of greater breadth along the end of the card than the spacing of the cards, so that the projections 6 of successive cards will overlap one another and thus lend support one to 75 another when the cards are assembled in the frame with the projections 6 engaged by the frame flanges f. This permits the use of lighter material for the cards than would be possible without such mutual support, and 80 at the same time insures greater rigidity of the assembled group of cards.

In order to reduce the thickness of the overlapping parts which extend under the frame flanges f, portions of one ply of the 85 folded parts, or so much thereof as overlap the projections of the next card, are cut away as shown at 7. In the form of the invention now being described the parts cut away are at the lateral extremities of the 90 folded over margin. Each card also has a pair of lateral projections 8 at its free margin to rest on the outer faces of the flanges f.

Referring now to the form shown in Figs. 5 to 8, the card body 1' has its upper margin folded over on line 2', and fastened as before by a plurality of fasteners 3. The free end 5' of the folded margin is creased on line 4' and bent on said creased line away from the card body to engage the top edge 95 of the next adjacent card in the series. The lateral projections 6' extend under the frame flanges f to support the group of cards when assembled in depending, overlapped, spaced relation; and as in the 100 former case, the projections of successive cards overlap and lend support one to another. In this case, however, the ply of the folded parts which is cut away, thus reducing the thickness of the overlapped portion 105 of the projections, is the body of the card at 7', instead of the end f of the folded mar-

- gin as in the other form. This makes it possible to swing the cards, for inspection or other purposes, from a point nearer the line of fasteners. The swinging of the cards 5 may be facilitated in the case of the depending cards, where gravity may be relied upon to hold the cards flat in the frame instead of the inherent stiffness of the cards as in the case of upstanding cards, by providing each 10 card with a crease 9, or similar hinge, on which the card body may be swung.
- The term card as used throughout the specification and claims denotes any index element of sheet material, whether of card-board, commonly so-called, or other suitable material.
- I claim:
1. An index comprising a series of cards arranged in overlapped, spaced relation, 20 with their margins exposed, each having a margin folded over upon the body of the card and fastened thereto part way from the fold, the end of the folded margin being free and constituting spacing means engaging the edge of the next adjacent card in the series, said cards having integrally formed projections extending laterally from the folded edges adapted to engage a channeled frame, said projections being of 30 greater breadth than the spacing of cards whereby the projections of successive cards will overlap and lend support one to another.
  2. An index comprising a series of cards arranged in overlapped, spaced relation, 35 with their margins exposed, each having a margin folded over upon the body of the card and fastened thereto part way from the fold, the end of the folded margin being free and constituting spacing means engaging the edge of the next adjacent card in the series, said cards having integrally formed projections extending laterally from the folded edges adapted to engage a 40 channeled frame, said projections being of greater breadth than the spacing of cards whereby the projections of successive cards will overlap and lend support one to another, one ply of the folded parts being cut 45 away to reduce the thickness of the overlapped portion of the projections.
  3. An index comprising a series of cards arranged in overlapped, spaced relation, 55 with their margins exposed, each having a margin folded over upon the body of the card and fastened thereto part way from the fold, the end of the folded margin being free and constituting spacing means engaging the edge of the next adjacent card in the series, said cards having integrally formed projections extending laterally from the folded edges adapted to engage 60 a channeled frame, said projections being a 65 channeled frame, said projections being of greater breadth than the spacing of cards whereby the projections of successive cards will overlap and lend support one to another, and the other 70 ply of said projections being cut away to reduce the thickness of the overlapped portion of the projections.
  4. An index comprising a series of cards arranged in overlapped, spaced relation, 75 with their margins exposed, each having one margin folded over upon the body of the card and fastened thereto part way from the fold, the end of the folded margin being free and constituting spacing means engaging the edge of the next adjacent card in the series, the material of the body of the card adjacent to the fold and the folded margin extending laterally beyond the side 80 edges of the card body to form a pair of two-ply projections adapted to engage a channeled frame.
  5. An index comprising a series of cards 85 arranged in overlapped, spaced relation, with their margins exposed, each having one margin folded over upon the body of the card and fastened thereto part way from the fold, the end of the folded margin being free and constituting spacing means engaging the edge of the next adjacent card in the series, the material of the body of the card adjacent to the fold and the folded margin extending laterally beyond the side 90 edges of the card body to form a pair of two-ply projections adapted to engage a channeled frame, one ply of said projections being of greater breadth than the spacing of the cards whereby the projections of successive cards will overlap and lend support one to another.
  6. An index comprising a series of cards arranged in overlapped, spaced relation, 95 with their margins exposed, each having one margin folded over upon the body of the card and fastened thereto part way from the fold, the end of the folded margin being free and constituting spacing means engaging the edge of the next adjacent card in the series, the material of the body of the card adjacent to the fold and the folded margin extending laterally beyond the side 100 edges of the card body to form a pair of two-ply projections adapted to engage a channeled frame, one ply of said projections being of greater breadth than the spacing of the cards whereby the projections of successive cards will overlap and lend support one to another.

Signed by me at North Tonawanda, N. Y., this 16th day of August, 1918.

JAMES H. RAND.
